UNITED STATES PATENT OFFICE.

ERNEST GOLDBERGER, OF DETROIT, MICHIGAN.

DISK CLUTCH.

1,383,717.

Specification of Letters Patent. Patented July 5, 1921.

Application filed January 30, 1920. Serial No. 355,206.

To all whom it may concern:

Be it known that I, ERNEST GOLDBERGER, a citizen of the United States of America, residing at Detroit, in the county of Wayne and State of Michigan, have invented certain new and useful Improvements in Disk Clutches, of which the following is a specification, reference being had therein to the accompanying drawings.

10 The invention relates to clutches of the disk type, and it is the object of the invention to obtain a simple and compact construction as hereinafter set forth.

In the drawings:

15 Figure 1 is a central longitudinal section of the clutch;

Fig. 2 is a sectional end elevation thereof.

A and B are the drive and driven shafts in axial alinement with each other. C is a 20 housing member mounted upon the drive shaft A and provided with a key D for transmitting the torque thereto. The outer peripheral flange E of this housing is provided on its inner face with a series of key-

25 ways F for engagement with one set of the disks. G is a head member mounted upon the driven shaft, B, being rotatively secured thereto by the key H. A hub portion of this head is provided with the annular recess I 30 in which is located a spring J. K is a co-operating head or clamping member, which is sleeved upon the shaft B and is provided with a grooved collar L for engagement with a pedal or other operating device. M

35 is an annular frame mounted upon the head G through the medium of posts N, which pass through apertures O in the member K, and is secured by the bolts P. These posts N are arranged close to the outer face of the 40 hub of the member G and pass through the central opening in the disks Q which engage the key-ways F. R are pins slidably engaging bearings in the annular member M and also passing through apertures in the mem-

45 bers K and G. The inner ends of these pins are secured to a spring abutment member S by cotter pins T, or other suitable means. U are driven disks which alternate with the disks Q, but are of smaller external diameter, so as to clear the flange E and key-ways F. These disks U are cut away for the passage of the posts N, but have portions V intermediate these posts which extend inward and are apertured for engage- 50 ment with the pins R.

With the construction as described, when

the parts are assembled, the pressure of the spring J upon the member S will place a tension upon the pins R, which having a shouldered engagement R' with the member K will communicate the pressure to the latter member. This will cause the clamping of the whole series of disks between the head G and the member K. To release the clutch, the member K is moved outward 60 through the medium of the grooved collar L and operating the pedal (not shown), this movement being transmitted by the compression of the spring J. In addition to the function of forming a connection between 70 the spring and the member K, the pins R also transmit the torque from the disks U to the driven shaft. Thus, the apertured portions V of said disks U transmit the torque directly to the pins R and the latter 75 through their bearings in the members G, K and M, which are rotatively fixed in relation to each other, communicate the torque to the driven shaft B.

One of the principal advantages of the 80 construction is the simplicity and compactness, which is largely due to the performance of the double function by the pins R. Thus, the forming of key-ways upon the member G is dispensed with and no additional clearance is required for the passage of the connection between the spring and the clamping plate.

What I claim as my invention is:

1. The combination with the rotary drive 90 and driven members in axial alinement, of a head secured to one of said members having a recess in the hub portion thereof, a spring in said recess, a spring abutment member, a series of pins passing through 95 said head connected at one end to said spring abutment, a clamping plate or head connected to said pins, and alternate drive and driven disks between said head and clamping plate, one set of disks being in 100 engagement with said pins for the transmission of torque therethrough to said head.

2. In a disk clutch, the combination with 105 rotary drive and driven members in axial alinement, of a housing secured to one of said members, a head secured to the other of said members within said housing forming one abutment for the series of disks, said head having a recessed hub, a clamping head longitudinally movable in relation to 110 the fixed head, a series of pins connected to said clamping head passing through aper-

tures in said fixed head, a spring abutment attached to the inner ends of said pins, a spring within the recess of the hub bearing against said spring abutment and the shoulder at the end of the recess, a series of alternately arranged drive and driven disks between said clamping head and fixed head, one set of disks being rotatively fixed to said housing and the other set of disks projecting inward and being apertured for engagement with said pins, and means for moving said clamping head away from said fixed head, said pins forming connections between said clamping head and the spring and also constituting torque members for connecting one set of disks to said head.

3. In a disk clutch, the combination with drive and driven members in axial alignment, of a housing secured to the one and a fixed head secured to the other within said housing, said fixed head having a recessed hub, a clamping head having a collar surrounding the shaft for actuating said head longitudinally, an annular frame surrounding said collar and provided with a plurality of posts passing through apertures in said clamping head and secured to said fixed head, a series of pins passing through bearings in said annular frame, said clamp-

ing head and fixed head, said pins having a shouldered engagement with said clamping head, a spring in the recess in said hub, a spring abutment connected with said pins, and a series of alternately arranged drive and driven disks between said fixed head and clamping head, one set of disks being in engagement with said housing and the other set having inwardly projecting portions apertured for engagement with said pins, whereby said pins constitute torque connections for said disks and also connections between said spring and clamping plate.

4. The combination with rotary drive and driven members in axial alignment, of a head secured to one of said members, a spring abutting at one end against said head, an abutment member for the other end of said spring, a series of pins passing through said head connected at one end to said abutment member, a clamping plate or head connected to said pins, and alternate drive and driven disks between said head and clamping plate, one set of said disks being in engagement with said pins for the transmission of a torque therethrough to said head.

In testimony whereof I affix my signature.
ERNEST GOLDBERGER.
